SCREW TYPE CLOSURE FOR CONTAINER
PIVOTALLY SUPPORTING A RESILIENTLY
MOUNTED PRESSURE CLOSURE FOR AD-
JACENT OPENING

John A. Johnson, Crawfordsville, Ind.

Application March 21, 1946, Serial No. 656,034

1 Claim. (Cl. 222—482)

1

This invention relates to a fire extinguisher of that type employing a chemical in powdered form, and relates particularly to means for preventing escape of the powder through the spraying or blowing nozzle before the extinguisher is to be used. A primary object of the invention is to provide an extremely simple and yet most effective cap for the dispensing nozzle which will always be available without danger of falling out or accidentally being removed. A further primary object of the invention is to provide such a structure in an exceedingly simple and yet durable form which will permit low-cost production.

These and other objects and advantages of the invention will become apparent to those versed in the art in the following description made in accordance with the accompanying drawing, in which:

Fig. 1 is a view in side elevation of an extinguisher to which the invention is applied;

Fig. 2, a view in end elevation; and,

Fig. 3, a view in fragmentary side elevation of the filling and dispensing and of the extinguisher in partial section on a line 3—3 in Fig. 2.

Like characters of reference indicate like parts throughout the several views in the drawing.

The fire extinguisher 10 is generally cylindrical in shape and is provided with a filler neck 11 with which is engaged a cap 12. In the form herein shown, this cap 12 screw threadedly engages over the outside of the neck 11. The neck 11 is positioned eccentrically of the body of the extinguisher 10 to provide space for the discharging or dispensing nozzle 13 through which the contents of the extinguisher 10 are expelled in the normal operation of applying the contents to the base of a fire.

A spring 14 has one end portion rockably attached to the cap 12 by any suitable means such as by a rivet 15. The other end of the spring 14 is provided with a rounded boss 16 spaced a radial distance from the rivet 15 to permit that boss 16 to center over the orifice of the nozzle 13 when the spring 14 is swung thereover. A gasket 17 which may be made of felt covers the boss 16 so that the spring 14 may compressly engage the felt around the edge portion of the nozzle orifice centered by the boss 16 pressing thereagainst.

The spring 14 normally tends to spring inwardly toward the end of the extinguisher 10, at least by a portion adjacent the rivet 15 to bear against the face of the cap 12 sufficiently to require that the spring 14 be lifted outwardly from the cap by its outer end to engage over the end of the nozzle 13 in order that the yielding pressure may be applied to retain the felt across the end of the nozzle. When the extinguisher is to be used, the spring 14 may be merely flexed to one side of the nozzle by revolving the spring about the rivet 15, the tension causing the spring

14 to swing inwardly toward the end of the extinguisher, and thereby any swinging of the spring 14 would cause its outer end to contact against the side of the nozzle 13 rather than to appear over its discharging end. That is the spring 14 when shifted to one side of the opening of the nozzle 13 will automatically spring back and thus not be permitted to return of its own accord across the opening of the nozzle. While this action is obtained, the presence of the spring 14 and its mounting on the cover 12 will not interfere with the removal of that cover to permit refilling of the extinguisher since the spring 14 is pivotally attached to the cover. This means that the cover 12 may be revolved on the neck 11 to remove it therefrom without any attention having to be paid to the spring 14 since the cover 12 may turn in a revolving manner in respect to the spring 14. Of course when the cap 12 is completely removed and then is returned after the filling operation, the spring member 14 will have to be swung around and its outer end lifted up to set over the end of the nozzle 13.

While I have herein shown the invention in the one best form as now known to me, it is obvious that structural details may be changed without departing from the spirit of the invention, and I therefore do not desire to be limited to that precise form beyond the limitations as may be required by the accompanying claim.

I claim:

Closure means for a container having a screw-threaded portion through which the container may be filled and a spray nozzle opening located to one side of and lying in a plane substantially normal to the axis of the threads of said portion, comprising a cover to screw-threadedly engage said portion to be advanced and retracted therealong; an elastic leaf member; means pivotally securing an end portion of the leaf member to said cover; said leaf member having a length sufficient to swing by its other end portion about said securing means across said nozzle opening, said other end portion being formed to seat compressibly against the margin of said nozzle opening whereby advancement of said cover on said portion will increase the pressure of said leaf member against the nozzle opening member.
